COURT

Henry B. Eaton, II, Scarsdale, N. Y., assignor to
 Church E. Gates and Company, New York,
 N. Y., a corporation of New York

Application February 20, 1935, Serial No. 7,327

7 Claims. (Cl. 20—1)

This invention relates to a court, to the deck and wall structure used therein, and to the method of making the same. More particularly the invention relates to a court having prefabricated deck and wall structure and to the method of making the prefabricated unit.

Prior to my invention various games have been played upon smooth courts requiring a smooth surface which will not interfere with the play, either by injury to the player's feet or by tripping the player, by producing irregular or freak rebounds of the ball or other playing piece from going to far afield if it should be missed by one of the players the court is ordinarily partially or entirely surrounded by a back stop or wall which is preferably openwork so as to permit free passage of wind and light therethrough.

Prior to my invention such courts have commonly been made by leveling and compacting the earth or by forming a hard surface thereon such as asphalt or concrete which will provide a permanently level rebound and playing surface and then erecting a net around the court to serve as a backstop. The building of the court in this way is both difficult and expensive, especially if the surface is made of asphalt or concrete; and if the surface is of compacted earth or clay it requires constant attention to keep it level and in condition for play, and furthermore cannot be used except when the ground is dry.

It is one object of my invention to provide for the use of wood for such courts. As compared with concrete, asphalt and even rolled clay the wood yields resiliently to the step of the players, and thus is much easier on their feet, relieving them from one of the prime sources of tiring. This difference has been noticed by many players, especially between sod or lawn courts and hard surfaced courts; but lawn courts have the disadvantage of not being perfectly smooth so that the surface may interfere with the rebound. Contrasted to this, wood may provide the most perfect rebound surface of any of the materials available for use in courts.

I do not claim to be the first to have tried wooden courts, but by my invention I utilize more fully the advantages of and eliminate the disadvantages heretofore experienced with wood in such use.

An object of my invention is to provide a court construction which can be prefabricated at the mill and easily erected or dismantled in any desired location, which will be relatively inexpensive, which will be superior for all playing purposes and which can be used under any and all weather

conditions. It is also an object of my invention to provide an improved deck construction for general use whenever a wooden or similar deck is suitable, an improved wall construction and an improved method by which walls can be constructed with flexible material held taut by a frame.

In the accompanying drawings I have illustrated a preferred embodiment of my invention by which these objects may be achieved and certain modifications thereof. These are given for purposes of illustration in order that the invention may be more readily understood and applied by those skilled in the art, and are not to be taken as in any way limiting the invention to the forms shown in the drawings.

Figure 1 is a perspective view of a court embodying my invention.

Figure 2 is a partial longitudinal sectional view of the court shown in Figure 1.

Figure 3 is a fragmentary plan view of one side panel before erection.

Fig. 3a is a fragmentary plan view of a panel similar to that shown in Fig. 3, but using a different type of wire mesh.

Figure 4 is a plan view partly broken away of the deck used in the court of Figure 1.

Figure 5 is a fragmentary elevation of the net section of the court.

Figure 6 is a longitudinal section similar to Figure 2 but on a larger scale and with central portions broken away. This section is taken on line 6—6 of Figure 7.

Figure 7 is a cross-section taken at the corner of the court just above the deck taken on line 7—7 of Figure 6.

Figure 8 is a fragmentary elevation taken at the bottom and end of Figure 7.

Figure 9 is a longitudinal section through a sleeper of the deck showing a modified construction.

Figure 10 is a perspective view of a modified fastening means with its central portion broken away.

Referring to the drawings, I have shown in Figure 1 a perspective on a small scale of a court constructed according to my invention, having a deck 10 and sidewalls 11. The deck as more clearly shown in Figures 2, 4 and 6 is constructed of sleepers 12 which may for example be 8 x 8 timbers and which may be held off the ground by concrete blocks 34 positioned so that the sleepers 12 lie level upon them.

On these sleepers are positioned panels 14 consisting of parallel boards or short planks 15

spaced a short distance from one another to provide for drainage and air circulation and held together by battens or cross members 16 which are nailed or screwed or otherwise secured to the 5 surface boards or planks 15, from the bottom so that no nails or other fastening means are present on the upper surface to work loose and trip or injure the feet of the players or interfere with the rebound of the playing pieces.

10 The end of the panels and preferably the end of each board therein may be secured to the sleepers 12 as shown for example in Figure 7 and this fastening should be by means of screws 37 or other means which will not work loose and

15 above the surface of the panels. In Figures 2, 4, 6, 7 and 8, I have shown each panel with two battens 16 between the ends. One of these battens is spaced farther from the adjacent end than the other, the difference being at least as 20 great as the width of the batten and the end of each batten extends beyond the sides of the panel. In this way the end of each batten extends under the adjoining panel, and the panels thus are interlocked and held flush at the playing surface.

25 As shown in Figures 6 and 7 the ends of the panel board are screwed to the sleepers, and the battens 16 are positioned intermediate between the sleepers. If battens are placed at or close to the end of the panels, they may themselves rest

30 upon the sleepers and serve not only to tie the ends of the panel boards 15, but also to secure them to the sleepers. This is shown for example in Figure 9 in which the battens 16 lie on the top of the sleeper 12. The battens are nailed to 35 the panel board 15 from the bottom and thus the nails 19 are securely held against working loose by the sleeper 12. The battens 16 are secured to the sleeper 12 by screws or nails 20 inserted between the panel boards 15 as shown.

40 In Figure 10, I have illustrated a stamped metal strip which may replace the batten 16 and the nails and screws 19 and 20. In this case a metal strip 16a serves as the batten and from this prongs 19a are stamped out and upwardly and 45 prongs 20a are stamped out and turned downwardly. These strips are preferably used with panels having intermediate battens 16 (which may also be similar to the battens 16a, but would preferably have only the turned up prongs 19a), 50 which serve not only to hold the panel boards flush between the sleepers 12, but also to hold the panels before they are assembled into the deck. In assembling the deck with these modified battens 16a, after the sleepers have been 55 laid in position the strips 16a may be laid along the top of the sleepers and the prongs 20a then driven into the sleepers 12. The panels 14 may then be laid onto the sleepers so that each board rests upon one of the prongs 19a and the boards 60 then driven onto these prongs so as to be secured thereby exactly as they would be secured by the nails 19 and the nails or screws 20 as shown in Figure 9.

65 As shown in Figure 6 the abutting ends of the boards 15 are preferably cut back slightly on an oblique angle from top to bottom. This expedient I have found serves to prevent small stones, etc. from becoming wedged between the ends and loosening the fastening means by serving as a 70 fulcrum to pry the boards apart when they are sprung by the weight of the players. With the ends cut back, as shown, any pieces small enough to pass between the ends of the boards will be readily accommodated in the wider space near 75 the bottom and consequently will not have any

serious effect upon the boards or their fastenings.

The back stops in this preferred embodiment of my invention are also secured to the sleepers 12 and are also erected from prefabricated units 5 or panels.

As shown, each panel consists of a frame and a facing of netting stretched over the frame. The frame, as shown, has side members 25, top and bottom members 26 and bracing struts 27. 10 The netting 28 is stretched over this frame and drawn onto the sides where it is tacked.

In order to hold the netting more securely and to provide a smooth continuous surface at the joints between adjacent panels I prefer to bevel 15 one side of each frame member as shown for example in Figure 7. A complementary strip 30 is fitted over this beveled portion after the wire has been secured in place and this strip is then secured to the corresponding frame member. A 20 most satisfactory way of achieving this result is to use frame members of rectangular cross section, but to saw one corner off on an angle, leaving a complementary strip which after the mounting of the netting 28 may be secured again 25 in its original position. The saw kerf is of substantially the same width as the thickness of the netting so that the surface of the strip 30 will necessarily be flush with and level from the corner of the frame member which establishes 30 the plane of the netting between frame members.

The design of this panel is intended to fit it for use in games where the ball or other playing piece is played after rebound from the back stop. In order to achieve this purpose it is necessary 35 that the netting 28 should at all times be held taut so that it will constitute a substantially plane and uniform surface. This I have achieved in the present invention partially by making the back stop of relatively narrow panels and partially by novel features of the design of these panels. By using prefabricated panels it is possible to stretch the netting uniformly by mill apparatus and to apply it in such uniformly stretched condition. By making relatively narrow 40 panels irregularities in the netting itself may readily be taken up by stretching and this is facilitated if a diamond mesh or other type of netting having the strands running in zigzag through the fabric is used, e. g., as shown at 28a 50 in Fig. 3a. The stretching of such zigzag strands tends to stretch the fabric in both directions so that even with somewhat irregular stretching and fastening at spaced points, the stretch will be distributed throughout the area of the netting 55 and a uniform result thus obtained.

An important and novel feature of these panels as shown for example in Figure 3 is that the frame members 25 and 26 are sprung inwardly slightly and held in this position while the netting 60 is being applied. The netting is then secured to the panel frame in this condition with as full and uniform stretching as is possible and the frame members then released. Upon release the frame members of course tend to again assume 65 a straight condition, and due to their resiliency will hold the netting taut and straight at all times. Furthermore, since the back stop is made by bolting these panels together, the bolts 38 as shown in Fig. 7 may be used to draw the 70 bowed members 25 back into line, if their own resiliency is not sufficient to adequately stretch the netting.

As already stated the back stop is erected by bolting the side frame members 25 of adjacent 75

panels together and securing the wall thus constructed to the playing deck 10.

If desired, the construction may be made more rigid by bolting the top frame member 26 to a top rail 32. This top rail may also serve to draw the sprung member 26 back into line and thereby further to stretch the netting.

The corner posts 33 connect the top rails 32 and thus make a rigid and self-sustaining wall.

10 The bottom frame members 26 may be similarly bolted to a bottom rail or directly to the boards 15 of the deck 10. I prefer, however, to use an anchor and brace members 35-36 as shown for example in Figures 6, 7 and 8.

15 The anchor member 35 as shown, is comprised of a metal strip or plate screwed or otherwise secured to the outer side of the frame members 26 of adjacent screen panels and either to the deck panels 14 or to the sleepers 12. The lower 20 ends of these plates 35 may be straight and screwed flat against the sleeper as shown at the sides of the court in Figures 6, 7 and 8, or bent under the floor panels as shown at the ends of the court.

25 In Fig. 5, I have shown a portion of the court structure in which the net posts 39 are mounted. As shown in this figure the posts 39 are secured by means of lag screws 40 to special cross members 41 which in turn are secured in any suitable 30 manner to the sleepers 12.

In the accompanying drawings and in the above specification I have attempted only to describe a preferred embodiment of my invention and various modifications thereof and the principles 35 involved therein in such a way that those skilled in the art may apply my invention to any given conditions and requirements. I have not attempted to mention exhaustively all of the various modifications which are known to me, but 40 I believe that in the light of the above specification and the accompanying drawings, all of these and others will be readily apparent to those skilled in the art and that numerous changes and modifications will therefore be made in applying 45 my invention to various conditions. All of these are of course to be included within the scope of the present application.

I claim:

1. A portable playing court comprising support 50 members spaced a distance greater than two and less than seven feet, separable deck members mounted thereon adapted to spring slightly between said support members under the step of a man, a vertical wall secured and braced on said 55 support members and comprising vertical panels secured together and flush at their inner surfaces, said panels comprising peripheral frames and

wire netting stretched across the face of the frame and secured on the sides thereof, said netting being sufficiently small mesh and sufficiently tightly stretched so that a ball rebounds therefrom substantially along the plane of its incident 5 flight as if rebounded from a rigid surface.

2. A playing court as defined in claim 1 in which the peripheral frames of the vertical panels are beveled toward their outer edges and leveled by a complementary strip secured thereover 10 which serves at once to clamp the netting and to provide a level rebound surface at the edge of said panel.

3. A panel adapted for use in an enclosure such as a playing court and the like which comprises 15 a peripheral frame and netting stretched thereon, the frame comprising members substantially rigid but capable of slight elastic flexing, said members being secured together near their ends and being flexed slightly inward whereby to exert elastic 20 tension on the netting to hold it taut and the netting being composed of zig-zag strands, whereby a stretching in either direction or at any point will tend to take up any slack even though such stretching is not directly applied in line with the 25 slack.

4. A panel as defined in claim 3 in which the frame members are beveled toward the outside and a complementary strip is secured thereon and over the netting whereby to clamp the netting securely to the frame and to provide a surface substantially flush and continuous with the plane of the netting within the frame. 30

5. A panel adapted for use in an enclosure such as a playing court and the like which comprises 35 a peripheral frame comprising members beveled toward the outer edge and having the netting secured thereon, and complementary strips secured thereon so as to clamp the netting between said strips and said members and to provide a flat surface substantially continuous with the plane of the netting between the strips. 40

6. An enclosure comprising a plurality of panels substantially as defined in claim 5 secured together in flush relation whereby to provide an 45 easily erected upward wall having a substantially true and continuous plane surface.

7. An enclosure comprising a plurality of panels substantially as defined in claim 3, their side frame members being drawn together in substantially flush relation whereby to tend to pull the frame members back into line and thereby to stretch the netting taut and form an open-work wall having a substantially plane and continuous surface from which balls will rebound in 55 a substantially predictable manner.

HENRY B. EATON, II.
